Specification of Letters Patent.

Patented Dec. 16, 1919.

Application filed November 15, 1918. Serial No. 262,739.

To all whom it may concern:

Be it known that I, JOHN C. SHAMBOW, a citizen of the United States, residing at Woonsocket, in the county of Providence and State of Rhode Island, have invented a new and useful Improvement in Shuttles, of which the following is a specification.

This invention relates to certain new and useful improvements in shuttles and pertains 10 more particularly to an improved form of means for preventing unthreading of the shuttle by reason of ballooning.

The object of the invention is to provide a simple form of means which can be easily, 15 economically and quickly produced and applied to the shuttle.

In brief, the invention proposes to provide a device for preventing unthreading which may be formed of a plate or piece of sheet 20 metal and which may be applied to the shuttle and held in its relation thereto solely by frictional contact of the sheet metal plate with the wood of the shuttle.

In the drawings—

25 Figure 1 is a top plan view of the invention applied to a shuttle, the latter shown in fragment.

Fig. 2 is a longitudinal sectional view of Fig. 1 showing the device in side elevation, 30 and

Fig. 3 is a side view of the device.

In proceeding in accordance with the present invention the device is formed from sheet metal or a metal plate preferably with 35 a somewhat rounded bottom 1 and an arm 2 terminating in a contracted finger 3 which is spaced from the arm and which terminates above the end 4 of the base 1, so as to provide a somewhat C-shaped configured guard. 40 The other end of the arm 2 is formed with an inclined edge 5 so that the thread may easily ride down the same. The arm 2, finger 3 and the end 4 of the base 1 provide an eye 6 through which the thread is passed.

45 As depicted in Fig. 2 of the drawings the finger 3 is deflected or bent so as to extend toward the bobbin receiving cavity C and the free extremity of the finger projects into a somewhat cup-shaped depression 7 formed 50 to the rear of a slot 8, the slot 8 extending transversely across the shuttle and being formed of such size so that the plate can be driven into the slot and held by frictional contact with the wall defining the slot. The

shuttle otherwise is provided with the throat 55 T and a threading slot S which leads into the usual delivery eye E at the outer side of the shuttle.

In operation, the thread is placed on the inclined edge 5 and then moved downwardly 60 through the throat T and threading slot S so as to pass beneath the free end of the finger 3, and into the eye 6. The depression 7 it will be observed from Fig. 1 is located to one side of the throat T and since the free 65 end of the finger projects into the depression 7 it will be seen that accidental unthreading of the shuttle is almost impossible due to the fact that the thread in order to disengage itself from the device must move down into 70 the depression 7 and then upwardly from under the finger 3, and as just stated, due to the parts 3 and 7 being located to one side of the normal line of travel of the thread accidental unthreading is rendered almost 75 negligible.

The device can easily be stamped out of sheet metal plates and driven into position, so that extraneous fastening means are not required.

Having thus described my invention, what I claim as new and desire to secure by Letters Patent is—

1. In a shuttle, a shuttle body having a throat and a threading slot, and being provided with a substantially cup-shaped depression to one side of the throat and also having a slot extending across and between the depression and the shuttle delivery eye, and a plate-like guard formed to be driven 85 into said transverse slot and having an arm provided with a finger the extremity of which latter is spaced from the adjacent part of the guard to form a thread receiving eye, said finger being deflected so as to extend partly into the cup-shaped depression, and the top edge of the arm being inclined 90 and merging into the finger.

2. In a shuttle, a shuttle body having a throat, a threading slot, a transverse slot, 100 and also a depression to the rear of the transverse slot, and a plate-like guard of substantially C-form driven at its base into the transverse slot and having the terminal of the outer portion thereof deflected and 105 extended partly into the depression.

3. In combination with a shuttle having a depression, a guard having a thread receiv-

ing eye located adjacent the depression and having a portion thereof extending partly into the depression.

4. In combination with a shuttle having a transverse slot and a depression adjacent thereto, a guard received in the slot and having a finger extending partly into the depression.

In testimony whereof I have signed my name to this specification in the presence 10 of two subscribing witnesses.

JOHN C. SHAMBOW.
